(57) **CLAIM**

The ornamental design for a control panel, as shown and described.

DESCRIPTION

FIG. 1 is a front perspective view of a control panel according to the present invention.

FIG. 2 is a top view of the control panel of FIG. 1.

FIG. 3 is a front view of the control panel of FIG. 1.

FIG. 4 is a first side view of the control panel of FIG. 1.

FIG. 5 is a second side view of the control panel of FIG. 1, opposite the first side shown in FIG. 4.

FIG. 6 is a rear view of the control panel of FIG. 1.

FIG. 7 is a bottom perspective view of the control panel of FIG. 1.

FIG. 8 is a front perspective view of a control panel according to the present invention.

FIG. 9 is a top view of the control panel of FIG. 8.

FIG. 10 is a front view of the control panel of FIG. 8.

FIG. 11 is a first side view of the control panel of FIG. 8.

FIG. 12 is a second side view of the control panel of FIG. 8, opposite the first side shown in FIG. 11.

FIG. 13 is a rear view of the control panel of FIG. 8; and, FIG. 14 is a bottom perspective view of the control panel of FIG. 8.

The shading lines are for illustrative purposes only and form no part of the claimed design.
